UNITED STATES PATENT OFFICE

BERNIS M. SHIPLEY, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed June 21, 1919. Serial No. 305,878.

This invention relates to attachments for cash registers and the like and is more particularly adapted to be used in connection with the type of cash register shown and described in Letters Patent of the United States issued to Thomas Carney, No. 497,860, on May 23, 1893, and to Joseph P. Cleal, No. 718,565, issued January 13, 1903.

The present device is shown attached to a machine of the type illustrated in the above mentioned Carney and Cleal patents, said machine being constructed and operating substantially the same as the machines shown in these patents and more particularly that shown in the Cleal patent. An object of this invention is to enable a merchant selling taxable goods to keep an account of all sales and also to keep an accurate account of all money taken in as tax which is collectible by the Revenue Department of the Government. This is accomplished by arranging the parts of the machine so that before the merchant can register the amount of sale of goods, he must first register the amount of tax on said sale. If the sale does not involve tax, a "no tax" key must be depressed before the amount of said sale can be registered.

It is a further object of the present invention to provide means for indicating the amount of tax, in addition to the regular means for indicating the amount of the sale. If the goods sold are non-taxable, the machine will indicate "no tax" and the amount of the sale.

With these and incidental objects in view, the invention consists in certain novel features of construction and combinations of parts, the essential elements of which are set forth in appended claims, and a preferred form or embodiment of which is hereinafter described with reference to the drawings which accompany and form part of the specification.

Of said drawings:

Fig. 1 is an end elevation of one of the tax key banks and shows its connections to the tax registering and indicating mechanism.

Fig. 2 is a top plan view of the transfer mechanism for transferring from the units to the tens element of the tax totalizer.

Fig. 3 is an end elevation of the mechanism illustrated in Fig. 2 except that the tens totalizer wheel is omitted.

Fig. 4 is a top plan view of the tax registering attachment, with parts broken away for the sake of clearness and illustrates the connection between said attachment and a machine of the above mentioned Cleal type which is shown partly broken away.

Fig. 5 is a fragmentary detail sectional view on line 5—5 of Fig. 6 and illustrates the construction of the indicator target guide.

Fig. 6 is a detail view of one of the indicator targets.

Fig. 7 is an end view of the indicator target shown in Fig. 6.

Fig. 8 is a vertical sectional view taken on line 8—8 of Fig. 1 looking in the direction indicated by the arrows.

Fig. 9 is a vertical sectional view taken on line 9—9 of Fig. 1 looking in the direction indicated by the arrows.

Fig. 10 is a front elevation of the tax totalizer and part of its operating mechanism, the side frames of the machine being broken away.

Fig. 11 is a detail sectional view, partly broken away of the mechanism for rotating the common operating shaft.

Fig. 12 is a vertical sectional view through a machine of the type described in the above mentioned Cleal patent, and to which the tax keyboard attachment is attached.

Fig. 13 is a detail sectional view through one of the key banks and shows the mechanism actuated by one of the keys.

Fig. 14 is a detail view of the interlock between the tax register and main register and shows the parts in the position they assume when a tax key has been depressed.

Described in general terms, the machine includes two separate keyboards, one for registering the regular amounts of a sale and one for registering the amount of tax on all taxable goods. These mechanisms controlled by said keyboards are so interconnected that a key in the tax keyboard must be operated before any of the regular amount keys can be manipulated, thus insuring the registration of the tax for each tax.

able sale. Proper indication is provided under the direct control of the keys.

Should a sale be non-taxable, a "no tax" key is provided and must be depressed before any of the regular amount keys can be operated thus indicating "no tax".

Described in detail the tax registering attachment includes two banks of keys 25 and 26 (Fig. 4). The keys 25 are for registering tens of cents and the keys 26 are for registering units of cents. A "no tax" key 27 is provided in the tens bank of keys for releasing the machine and for indicating when a sale does not involve the taxation.

Means is provided for preventing the depression of more than one key at a time in a bank. This means includes lugs 28 (Figs. 1 and 13) secured to the keys 25 and 26, which cooperate with key stops 29 pivotally mounted on frames 30 (Figs. 1 and 4) carried by rods 31 mounted in side frames 32 and 33. Secured to the frames 30 are cover plates 34 which have slots (not shown) through which the keys project and which serve as guides for said keys. The key stops 29 are so arranged that when any key is depressed its lug 28 will be moved between two of the key stops, rocking them apart and holding them in these positions thus closing the spaces between all the other key stops 29, which prevents any of the other keys from being depressed until the depressed key has been released.

The lower ends of the keys are pivotally mounted at 38 on differential drivers 39 loose on a rod 40 carried by the frames 32 and 33. The keys 25 and 26 are laterally spaced and guided at their lower ends by the drivers 39 and thin guides 41 mounted on and extending from the rod 40 to a rod 42 carried by the frames 32 and 33. These guides 41 are laterally spaced on the rod 42 by means of collars 43 (Fig. 9). Through this arrangement the differential drivers 39 and the keys are always held in perfect lateral alignment.

The differential drivers 39 are provided with slots 44 (Figs. 1 and 13). These slots 44 are graduated commensurate with the values of the keys. The group of differential drivers 39 for the units bank of keys is provided with slots graduated identically the same as those shown in Fig. 1 associated with the tens bank of keys. The slot 44 in the driver 39 (associated with the "no tax" key 27) is not graduated but is a true arc swung from the center of the rod 40 upon which all drivers 39 are pivoted. The purpose of this will be hereinafter described.

Cooperating with the slots 44 associated with the tens bank of keys, is a rod 48 carried by an arm 49 and a lever 50 rigidly connected by a sleeve 45 (Figs. 8) loose on a rod 51 mounted in the frames 32 and 33. Cooperating with the slots 44 associated with the units bank of keys is a rod 52 (Fig. 8) car-

ried by an arm 53 and a lever 54 rigidly connected by a sleeve 46 loose on the rod 51. The rods 48 and 52 are held in their normal positions by arms 55 (Figs. 1, 8 and 13) loose on the rod 40, and held in engagement with said rods 48 and 52 by means of springs 56. Integral with the levers 50 and 54 are totalizer actuating segments 57 and 58 which cooperate with a tax totalizer to be hereinafter described.

From the above description it will be readily seen that when, for example, the "4" key in the tens bank is depressed the differential driver 39 to which this key is pivotally connected will be rocked clockwise, whereby the slot 44 in this driver will move the rod 48 downwardly, to rock the arm 49 and the lever 50 counterclockwise and move the segment 57 upwardly to the fourth position, thus registering "4" on the tens totalizer wheel, to be hereinafter described. When the rod 48 is once started downward, it, by its engagement with the edges 47 of the unoperated differential drivers 39, prevents any of the latter drivers from being moved.

The means for returning the key and the mechanism associated therewith to normal positions, includes an arm 59 (Fig. 1) integral with each of the differential drivers 39, each arm 59 having a slot 60 cooperating with a flattened rod 61 carried by a restoring arm 62 and a restoring lever 63 (Figs. 1, 8 and 13) fast on a shaft 64 carried by the frames 32 and 33. Stretched between the rear end of the lever 63 and a stud 65 carried by the frame 33 is a restoring spring 66.

From this description it will be clear that when the differential driver 39 is rocked clockwise by the depression of the key, the arm 59 will be rocked clockwise, and through the slot 60 and the rod 61 rock the restoring arm 62, the shaft 64 and the restoring lever 63 counter clockwise, thus stretching the restoring spring 66. After the key has been released by means which will be hereinafter described, the restoring spring 66, having been put under extra tension, will rock the lever 63, the shaft 64 and arm 62 clockwise and cause the rod 61 to force the arm 59 and consequently the differential driver 39 counter clockwise to normal position, thus raising the key to its normal position.

When an operation of a key 25 and 26 is required to register a tax, these keys must be simultaneously depressed, because when any one of the arms 59 begins to rock clockwise upon depression of a key 25 or 26, this arm will cause the rod 61 to be moved to engage the projections 67 of all other arms 59, thereby preventing movement thereof, and consequently preventing depression of any other key 25 or 26. If, however, two keys are depressed simultaneously, the slots 60 of both arms 59, corresponding to the keys being de-

pressed, will embrace the rod 61 thereby permitting continued depression thereof.

Means is provided for locking any of the tax keys or the "no tax" key in depressed position until after one of the amount keys has been depressed. Upon the depression of the regular amount keys, to be hereinafter described, this locking means is released and allows the restoring spring 66 to return the tax keys in the manner above described. This mechanism includes an arm 70 (Figs. 1, 8 and 13) integral with the restoring lever 63. Pivotedly mounted on the arm 70 is a catch 71, the forward end of which is held in contact with a latch plate 72 by means of a spring 73 stretched between the rear end of a catch 71 and the pin 74, carried by the restoring lever 63. The latch plate 72 is mounted on two studs 75 carried by the frame 33. When the lever 63 is rocked counter clockwise by the depression of a key, as previously described, the catch 71 is moved forwardly until it strikes a trip arm 76 (see also Fig. 14) pivotally mounted at 77 on an arm 78 fast on a shaft 79, and rocks said trip arm 76 clockwise until a pin 80, carried thereby, engages a finger 81 of a latch arm 82 also pivoted at 77 to the arm 78. The pin 80 rocks the latch arm 82 clockwise until a shoulder 83 thereon is disengaged from a block 84 secured to the side of the latch plate 72. The catch 71 is provided with a shoulder 88 which hooks over a point 89 on the latch plate 72 when said catch reaches the end of its forward movement (Fig. 14). A spring 90 stretched between the pin 80 and a pin 91, carried by the arm 78, holds the arms 82 and 76 in their normal positions.

When the catch 71 engages the trip arm 76 (Fig. 14), and rocks it clockwise, as above mentioned, the pin 80, carried by said arm, rocks the latch arm 82 clockwise and disengages the shoulder 83 thereof from the block 84, thereby allowing the arm 78 secured to the shaft 79, which shaft is rigid with the regular key coupler to be later described, to be rocked clockwise so that the regular amount keys also to be hereinafter described may be operated. After the latch arm 82 has been released from the block 84 and when the arm 78 is rocked clockwise, as will be later described, said arm 78 moves the latch arm 82 downwardly in the direction of its length until a foot 85 thereof engages a pin 86 on the catch 71 and rocks said catch counter clockwise thereby disengaging it from the latch plate 72 to allow the restoring spring 66 to act to return the tax keys and differential drivers 39 to normal positions.

60 A full stroke device is also provided so that after a tax key 25, 26, or the "no-sale" key 27 has been slightly depressed, the operator must depress the key the full amount before said key can be returned to normal position.

65 This full stroke device includes a pawl 95

(Figs. 1 and 8) pivotally mounted on the side of the arm 70 and held in normal position by a spring 96 stretched between a pin 97 carried by said pawl and a pin 98 carried by the arm 70. The lower end of the pawl 95 is provided with a square tooth 94 which cooperates with a notched retaining plate 99 mounted on the studs 75 adjacent the latch plate 72.

When any one of the keys 25, 26 or 27 is depressed and the arm 70 rocked counter clockwise the square tooth 94 of the pawl 95 engages the notches on the retaining plate 99 and rocks the pawl 95 clockwise, thereby positioning the tooth 94 so that it cooperates with the notches on the retaining plate 99 and acts as a retaining pawl thereby making it impossible to return the arm 70 until said arm has been moved counter clockwise a distance sufficient to cause the tooth 94 of the pawl 95 to pass off the right-hand end (as viewed in Fig. 1) of the retaining plate 99. This pawl 95 also acts as a full stroke device for compelling the keys to be entirely returned to normal positions, after having been depressed to register any amount of tax. In operating as a full stroke for the return of the key, the pawl 95 as it strikes the right-hand end of the retaining plate 72 when the arm 70 is started in its clockwise direction, is rocked in the reverse direction from that in which it is rocked during a depression of the key and the square tooth 94 of said pawl cooperates with the notches in the retaining plate 99 to prevent counter-clockwise movement of the arm 70 after said arm has started clockwise towards its normal position.

Tax totalizer

The totalizer for accumulating the amounts of taxes commensurate with the values of the keys depressed includes, six totalizer wheels 101 (Figs. 1 and 10) loose on a shaft 102 carried by parallel arms 103 and 104 fast on a shaft 105 mounted in the frames 32 and 33. The units and tens amount wheels 101 each have secured to the side thereof a star wheel 106. Secured to the units star wheel 106 by means of a hub 107 is a pinion 108 (Fig. 10) meshing with an actuating pinion 109 which, in turn, meshes with the actuating segment 58. The pinion 109 is mounted on a stud 110 carried by the frame 33. Secured to the side of the tens star wheel 106 is a pinion 111 (Figs. 2, 3 and 10) which meshes with an actuating pinion 112 (Figs. 1 and 10) which in turn meshes with the actuating segment 57. The pinion 112 is carried by a V shaped arm 113 fast on a rod 114 carried by the frames 32 and 33.

As previously described, the actuating segments 57 and 58 are moved upwardly commensurate with the values of the keys depressed in the tens and the units banks re-

spectively. The upward movement of these segments causes the actuating pinions 109 and 112, and consequently the pinions 108 and 111 to be rotated corresponding to the values of the keys depressed, thereby rotating the units and tens totalizer wheels 101 commensurate with the values of the operated keys.

The means for transferring from the units to the tens totalizer wheel includes a disk 117 (Figs. 2, 3 and 10) secured to the side of the units wheel 101. Integral with the disk 117 is a transfer tooth 118 so positioned in relation to the units totalizer wheel 101 that when said wheel passes from "9" to "0" the transfer tooth 118 engages a half-round pin 119 carried by a transfer arm 120 fast on a shaft 121 and rocks said transfer arm counter clockwise (Fig. 3). The transfer arm 120 carries a pin 122 which enters a cam slot 123 formed in the V-shaped lever 113. The free end of the transfer arm 120 is shaped to form an obtuse angle, normally engaged by a notch 125 of a spring pressed retaining arm 124 to hold the transfer arm 120 in its normal position. When the tooth 118 engages the pin 119 and rocks the transfer arm 120 counter clockwise, as above described, the V-shaped lever 113 through the pin 122 and cam slot 123 is rocked clockwise. The counter-clockwise movement of the transfer arm 120 moves the free end thereof from the notch 125 into a notch 126 in the retaining arm 124, and said transfer arm is held in this position until positively restored by means which will be hereinafter described. The clockwise rocking of the V-shaped lever 113 causes the pinion 112 to roll over the actuating segment 57, thereby turning the pinion 111 and consequently the tens totalizer wheel 101 one step, or in other words, adding "one" on this wheel.

The transferring from the tens wheel 101 to the hundreds wheel 101 and so on through the higher order wheels 101 is accomplished by the usual Geneva star wheels 127 (Fig. 10) and gears 128 and as this Geneva transfer is old and well known in the art it will not be described herein. These transfer elements are carried by a shaft supported in the arm 103 and an arm 129 secured to the shaft 105. For a detailed description of a transfer device of this type reference may be had to Letters Patent of the United States, issued to Thomas Carney, No. 532,762, on January 22, 1895.

After the transferring from the units to the tens amount wheel has taken place the totalizer pinions 108 and 111 are disengaged from the actuating pinions 109 and 112.

The means for disengaging the totalizer pinions 108 and 111 from the actuating pinions 109 and 112 includes an arm 130 (Figs. 1 and 10) integral with the totalizer supporting arm 104. The arm 130 carries a pin 131 which projects into a cam slot 132 formed in a totalizer engaging and disengaging lever 133 (Figs. 1, 8 and 10) fast on a shaft 134

mounted in the side frames 32 and 33. Integral with the lever 133 is an arm 135 (Fig. 4). Fast on the shaft 134 and parallel with the arm 135 is an arm 136 (Figs. 1 and 8). The arms 135 and 136 carry a rod 137 which projects through slots 138 formed in the differential drivers 39.

Near the end of the clockwise movement of any one of the drivers 39, the rod 137 is moved downwardly by the slot 138 thus causing counter clockwise movement of the arms 135 and 136 and consequently of the shaft 134 and totalizer engaging and disengaging lever 133. Each of the differential drivers 39 is provided with a clearance slot 139 leading off from the slot 138 to permit downward movement of the rod 137 with respect to the drivers 39 not rocked from normal position. This counter clockwise movement of the lever 133, through the cam slot 132 therein and the pin 131 causes a counter clockwise rocking of the arm 130 and consequently of the arms 103 and 104, thereby disengaging the totalizer pinions 108 and 111 from the actuating pinions 109 and 112 respectively.

During the disengaging of the totalizer pinions 108 and 111 from their actuating pinions 109 and 112 respectively the transfer mechanism previously described is restored to normal position. The means for accomplishing this includes a transfer restoring arm 140 (Figs. 1, 2 and 3), fast on the shaft 121. The arm 140 carries a stud 141 which cooperates with a toe 142 integral with the totalizer supporting arm 104.

It will be remembered from the previous description that when the transfer takes place, the transfer arm 120 and consequently the shaft 121 are rocked counter clockwise (Fig. 3), this causing the transfer restoring arm 140 to be rocked likewise. When the totalizer supporting arm 104 is rocked counter clockwise, as above described to disengage the tax totalizer from the actuating pinions 109 and 112, the toe 142 of the arm 104 strikes the stud 141 and rocks the transfer restoring arm 140, the shaft 121 and consequently the transfer arm 120 clockwise to normal positions. This movement, however, does not happen until after the totalizer pinion 111 has been disengaged from the actuating pinion 112, and therefore the amount which was transferred to this pinion 111 and its totalizer wheel 101 will remain thereon. The restoring of the transfer arm 120 to normal position, through the pin 122 and cam slot 123, rocks the V-shaped lever 113 counter clockwise to normal position ready to receive the next transfer operation when the units wheel passes from "9" to "0". The restoring of the transfer arm 120 removes its free end from the notch 126 to the notch 125 in the arm 124, and said arm 120 is thereby held in its normal position.

Means is provided for aligning the units

and tens totalizer wheels when the totalizer is disengaged from the actuating pinions 109 and 112. Means is also provided for aligning the totalizer engaging and disengaging lever 133 in either of its two positions. The aligning means for the units and tens totalizer wheels includes two spring pressed pawls 145 (Figs. 1 and 10) fastened together by means of a hub 146 loose on the shaft 105. These pawls are in the same planes with the star wheels 106 of the units and tens totalizer wheels and are in such relation thereto that said star wheels engage the lower ends of the pawls 145 before the pinions 108 and 111 are entirely disengaged from the pinions 109 and 112, thereby insuring positive alignment of the totalizer wheels when they become fully disengaged to allow restoring of the tripped transfer device.

One of the pawls 145 is normally held against a collar 147 mounted eccentrically on a stud 148 carried by the side frame 33. The collar 147 may be turned on the stud to adjust the pawls 145 in the exact proper relations to the star wheels 106 and after adjustment of said collar it may be locked in position by means of a screw 149.

The means for aligning the totalizer engaging and disengaging lever 133 includes two notches 151 and 152 formed in the upper end thereof. The notch 151 is normally engaged by a pawl 153 loose on the shaft 105, said pawl is held by a spring 154 stretched between the forward end of the pawl 153 and a stud 155, carried by the side frame 33. When the lever 133 is rocked counter clockwise to disengage the totalizer, the pawl 153 is disengaged from the notch 151 and enters the notch 152, thereby holding said lever and the totalizer in alignment until it is again engaged with its actuating pinions.

When the "no tax" key 27 is depressed, its corresponding driver 39 is rocked clockwise but as the slot 44 therein is on a true arc about the center of the rod 40, as previously described, the lever 50 and the actuating segment 57 will not be moved, therefore nothing will be added upon the totalizer when the "no tax" key is depressed.

50 Tax indication

The means for indicating the amount of tax commensurate with the value of any of the depressed tax keys includes two series of indicator targets 160 (Figs. 1 and 4) slidably mounted between L-shaped guides 161 secured to the inside of a target box 162. A special indicator target 163 is provided for the "no tax" key. Each indicator target 160 and 163, has two double flanges 165 (Figs. 5 to 7) cooperating with the guides 161 to stabilize the targets as they are raised and lowered. The lower end of each indicator target has a pair of loops 166 to support the targets on the upper ends of links 167 connected to

indicator lifting arms 169 by pivot pins 168. The indicator lifting arms 169 are pivoted on the rod 40 between the differential drivers 39 and the guides 41. The indicator target box 162 is secured to a yoke 170 (Figs. 4 and 8) integral with parallel arms 171 fast 70 to the side frames 32 and 33.

The means for raising the proper target into view when a key is depressed includes an indicator operating arm 175 (Fig. 1) integral with the differential driver 39. The 75 arm 175 carries a pin 176 upon which the indicator lifting arm 169 normally rests. From this description it will be seen that when any one of the keys is depressed and the corresponding differential driver 39 is rocked clockwise, as previously described, the indicator operating arm 175 through the pin 176, raises the associated indicator lifting arm 169, link 167, and target 160 so that the characters thereon will be exposed to view 80 above the target box 162.

The means for holding the target in view after it has been raised includes a latch arm 177 (Figs. 1 and 9) integral with the indicator lifting arm 169. Held in engagement 90 with the back of the latch arm 177 by means of a spring 178 is a retaining bail 179 carried by parallel arms 180 loose on a rod 181 carried by the side frames 32 and 33. When the indicator lifting arm 169 and arm 177 are raised to expose the indicator target to view, the retaining bail 179, engages underneath a shoulder 182 formed on the retaining arm 177 and holds the indicator target in view until 95 released by the depression of a key in a subsequent operation of the machine.

Means is provided for concealing the target until it is has been raised to its proper height. This means includes a flash 185 (Figs. 1, 4 and 9) which surrounds the target box 162. Connected to the flash 185 by pin and slot connection are two parallel flash-operating arms 186 fast upon a shaft 187 mounted in the side frames 32 and 33. Integral with the right hand arm 186 (as viewed in Figs. 4 and 8) is a segment 188 which meshes with another segment 189 integral with the lever 63 (Fig. 1).

From this description it can be readily seen, when the lever 63 is rocked counter clockwise (Fig. 1), as previously described, that through the segments 188 and 189, the shaft 187 and the flash-operating arms 186, will be rocked clockwise to raise the flash 185 simultaneously with the raising of the indicator target, it being remembered that the raising of the target and the rocking of the arm 63 are both caused by the depression of any of the keys 25, 26 or 27. Upon release 115 of the key and its restoration to normal position, the lever 63 is rocked clockwise to normal position, and therefore the flash-operating arms 186 will be rocked counter clockwise, to lower the flash 185 to its normal home 120 125 130

position while the lifted target remains exposed to public view.

In a subsequent operation of the machine a cam edge 190 on the latch arm 177 rocks the retaining bail 179 and the arms 180 counter clockwise thereby releasing the previously raised indicator target and allowing it to return to normal position.

10 *Amount registering mechanism*

The mechanism for registering and indicating the amount of the sale after the tax has been registered by the means previously described, will be only briefly described here, as this mechanism is substantially the same as that fully illustrated and described in the above mentioned Carney Patent, No. 497,860, and Cleal Patent, No. 718,565, and reference to these patents may be had for a more minute description of these mechanisms. Described briefly, those mechanisms, as substantially illustrated here, include a series of amount keys 195 (Figs. 4 and 12), pivotally mounted upon a rod 196 carried by side frames 197 and 198. Common to all of the keys 195 is a key coupler 199 (Figs. 4 and 12) pivotally mounted at its right hand end in the frame 198, by means of a trunnion 191 (Figs. 4 and 11), its left hand end being fast upon the shaft 79 (Fig. 4), previously described, mounted in the side frame 33 and the frame 197. Each of the pivoted keys 195 is provided with a notch 200 adapted to cooperate with a lip 201 formed on the rear edge of the key coupler 199 when any of the pivoted keys is depressed at its outer end. Suitably mounted in the side frames 197 and 198 is a transverse rotation shaft 202 (Figs. 11 and 12) given a complete rotation upon each oscillation of the key coupler 199 by a mechanism shown in Fig. 11. By referring to said figure, it will be noted that at its right hand end the key coupler 199 is provided with a stud 203 which projects into an elongated slot 204 formed in a vertically reciprocable double rack 205. At its lower end the double rack 205 is provided with an open slot 206 receiving a stud 194 mounted on the right hand side frame 198. At its upper end the rack 206 is also slotted, and on the side walls of the slot, the rack 205 is provided with oppositely faced rack teeth 207 which cooperate with a pinion 208 fast on the rotation shaft 202. This mechanism is of substantially the same construction and operation as the mechanism shown in the aforesaid Carney Patent, No. 497,860, and Cleal Patent, No. 718,565, and for the accomplishment of the same purpose, that is, the giving of a complete rotation to the shaft 202 at each oscillation of the key coupler 199, the rotation being in the direction of the arrow, as illustrated in Figs. 11 and 12. In order to prevent a retrograde movement of the shaft 202, 60 a ratchet or full-stroke disk 209 is made fast

to the right hand end of the shaft 202 and cooperates with a full stroke pawl or lever 210 pivoted at 211 to the right side frame 198 of the machine, and held in engagement with the ratchet 209 by means of a spring 212 seated in a block 213 on the right hand side frame 198.

It will thus be seen that upon each complete depression and return of the pivoted key levers, the key coupler 199 will be oscillated and through the connections shown in Fig. 11 and just described, a single rotation will be given to the shaft 202. The function of the key coupler 199, as is well known in the art, is to permit the starting of an operation of two or more keys, for example, the "\$1.00" key and the "70¢" key, and then the completion of the operation by pressing either one of those keys. By reason of the engagement of the lip 201 of the key coupler 199 with the notches 200 in the keys, the "\$1.00" key and the "70¢" key will be fully operated by the complete depression of either one of the two.

From the mechanism just described, it can be seen that it is necessary to oscillate the key coupler 199, and from the mechanism previously described in connection with the tax keys 25 and 26 it can also be seen that before the key coupler 199 can be oscillated, it must of necessity be free to oscillate. In other words the latch arm 82, Figs. 13 and 14, which it will be remembered is connected to the arm 78 fast on the key coupler shaft 79, must be released from the block 84 in order to allow the arm 78, the shaft 79 and the key coupler 199 to be rocked. The releasing of this latch arm 82 from the block 84, as has been previously described, is caused by the depression of one of the keys 25 or 26 in either of the two banks representing the taxable amounts. After a key in either one of the tax banks has been depressed, and released the latch arm 82, any of the keys 195 (Fig. 4) may be depressed to register the amount of the sale upon a "purchase" totalizer, to be hereinafter described.

It will also be remembered that when one of the tax keys is depressed, the catch 71, as it rocks the trip arm 76 to disengage the latch arm 82 from the block 84, hooks over the point 89 of the plate 72. This construction makes it necessary for the operator to depress one of the keys 195 to register the amount of sale into purchase totalizer after one of the tax keys 25 or 26 has been depressed to register the tax of a sale into the tax totalizer to complete the registration before another tax key can be depressed. The depression of one of the keys 195, it will be remembered, raises the key coupler 199 and upon release of the key 195 the key coupler 199 rocks clockwise (Figs. 11 and 12) and causes the shaft 79 to be rocked counter clock- 130

wise (Fig. 1) thereby rocking the arm 78 in the same direction and moving the latch arm 82 in the direction of its length to normal position, whereby the shoulder 83 thereon again engages the top portion of the block 84 and locks the key coupler and consequently the keys 195 in their normal positions.

Indicating mechanism

10 Slidably mounted in the guide frames 215 and 216 (Fig. 12) just above the rear ends of each of the keys 195, is an indicator bar 217 which carries at its top one of a series of indicating tablets 218 of a type fully shown 15 and described in the hereinbefore mentioned Carney Patent, No. 497,860, and Cleal Patent, No. 718,565. The indicator bars 217 are yieldingly held in their lowermost positions by springs 219 so that the lower ends of said 20 bars contact the rear ends of the pivoted keys 195. Each of the indicators 218 bears a special character or characters which are preferably identical with the characters appearing on the forward ends of their appropriate pivoted keys.

When any of the keys 195 are depressed, the corresponding indicator bars 217 will be elevated against the tension of the indicator springs 219 carrying the tablets 218 upwardly 30 until a projection 220 carried by each of the indicator bars, passes above a retaining bail 221 pivoted at 222 at each end to the side frames 197 and 198. The construction and operation of the bail 221 are old and well 35 known in the art and will not be described in detail here. It is sufficient to state that the purpose of the bail 221 is to hold the indicator bars 217 appropriate to the depressed keys in elevated positions between operations 40 of the machine, so as to sustain an indication between operations of the machine, thereby showing which key or keys were depressed in the previous operation. It will thus be seen that when any one of the key levers 45 195 is depressed, the proper indicator tablet 218 will be raised and publicly exposed through sight openings in the cabinet commonly provided in cash registers, so as to indicate which one of the key levers has been 50 operated.

"Purchase" totalizer

The totalizer for accumulating the amounts as registered by the keys 195, is substantially 55 the same as that illustrated and described in the above mentioned Cleal patent. Reference to this patent may be had for a detailed description of said totalizer.

60 Described in brief terms, the totalizer includes totalizer wheels 228 (Fig. 12) each having secured to the side thereof a ratchet 229 and a pinion 230. The totalizer wheels are loose upon a shaft 231 carried by a frame- 65 work 232 pivotally mounted upon brackets

carried by a tie bar 233 which connects the side frames 197 and 198.

Loose upon a shaft 234 carried by the side frames 197 and 198 is an actuating frame 235 having secured thereto a segment 236 arranged to be engaged by the totalizer pinion 230 at the proper time and in a manner to be hereinafter described. Cooperating with a rod 237 in the rear portion of the frame 235 is an actuator controller 238, the lower end of which is pivotally mounted on the key 195.

Pivoted to the right hand end of the totalizer frame 232 is a lever 239 formed with two arms at its right hand end (Fig. 12), each of said arms carrying an anti-friction roller 240. The two anti-friction rollers 240 cooperate with a cam 241 fast on the rotation shaft 202. The lever 239 is pivoted to the totalizer frame 232 at 242 and its forward end 243 strikes a pin 244 mounted in the frame 232. Upon rotation of the shaft 202 by the depression of the key 195, as previously described, the cam 241 will act upon the lever 239 and rock the totalizer frame 232 clockwise about its pivot 245, whereby the pinion 230 is carried into engagement with the segment 236.

The depression of the key raises the actuator controller 238 into engagement with the rod 237 carried by the actuating frame 235, thereby rocking said frame and consequently the segment 236 counter clockwise, thus rotating the pinion 236 a distance commensurate with the value of the key which has been depressed.

The transferring from a lower order to a higher order element of the totalizer is accomplished by means of a transfer tooth 250 integral with the disk 251 secured to the side of the totalizer wheel 228. This transfer tooth 250 is so positioned, that as a wheel passes from "9" to "0" said tooth 250 engages a trip pawl 252 and rocks said trip pawl counter clockwise, thereby allowing a transfer pawl 253 normally held in the position shown in Fig. 12 by the trip pawl 252, to be rocked clockwise through the action of a spring 254, pressing against the forward end of the transfer pawl 253. The pawl 253 is pivotally mounted upon a transfer operating lever 255 which in turn is pivotally mounted on the frame 232 on an axis which coincides with the pivotal axis 245 of the frame itself. The transfer operating lever 255 carries an anti-friction roller 256 which cooperates with a cam 257 fast on a rotation shaft 202. At the proper time the cam 257 engages a latch plate 258, rocking said latch plate clockwise and thereby releasing the transfer operating lever 255 so that as the cam 257 continues in its rotation, it will engage the anti-friction roller 256 and rock the lever 255 clockwise, whereby the transfer pawl 253 when tripped engages the ratchet 229 of the next higher order totalizer 120 element and advances said element one step.

125 130

Operation

For convenience in describing the operation of the machine, let it be assumed that the merchant has a taxable sale of "90¢" to register. On a ten percent basis, the tax on this amount would be "9¢".

To register this amount, the merchant first depresses the "9" tax key 26 in the units bank (Fig. 4) thereby rocking its appropriate differential driver 39 (Fig. 1) clockwise and the slot 44 in this driver will move the rod 52 (Fig. 8) downwardly, thereby moving the actuating segment 58 upwardly a distance commensurate with the value of the "9" key, the upward movement of the segment causing a rotation of the actuating pinion 109 (Fig. 10) and totalizer pinion 108 a distance of nine spaces, whereby "9" will be registered upon the units wheel 101 of the tax totalizer. During the clockwise movement of the differential driver 39, the pin 176 rocks the associated indicator lifting arm 169, (Figs. 1 and 13) and its corresponding link 167 is raised and exposes the "9" indicator target 160 to view. After the target has been lifted, the spring 178 rocks the retaining bail 179 beneath the shoulder 182 of the latch arm 177, and holds the target exposed until it is released by a subsequent operation of the machine. During the raising of the target, it is concealed from view by means of the flash 185 which, it will be remembered, is raised by the flash-operating arms 186 through the operation of the segments 188 and 189 which in turn are rocked by the slot 60 in the arm 59 integral with the differential driver 39. The slot 60, it will be remembered, also causes a counter clockwise movement of the arm 70, whereby the catch 71 strikes and rocks the trip arm 76 which rocks the latch arm 82 clockwise releasing its shoulder 83 from the block 84. The catch 71 finally hooks over the point 89 of the latch plate 72 and remains in this position. Near the end of the clockwise movement of the differential driver 39, through the slot 138 therein and rod 137, the totalizer engaging and disengaging lever 133 is rocked counter clockwise to disengage the totalizer pinions 108 and 111 from the actuating pinions 109 and 112. After the merchant has made a complete depression of the "9" key causing the elements to be operated as just described, he then depresses the "90" key 195 (Fig. 4) to register the amount of the sale. The depression of this key rocks the key coupler 199 counter clockwise, causes the "90" indicator 218 to be exposed to view, and rocks the segment 236 to accumulate the amount of sale on the totalizer wheels 228. The shaft 202 is also given a complete rotation thereby rocking the totalizer frame 232 so that the totalizer elements will be engaged with their actuating segments 236 and disengaged therefrom after the amount has been accumulated

thereon. The depression of the "90" key and the consequent rocking of the key coupler 199 rocks the shaft 79 clockwise (Figs. 1 and 13) thereby rocking the arm 78 clockwise and moving the latch arm 82 downwardly in the direction of its length a distance sufficient to cause its foot 85 to engage the pin 86 on the catch 71 and rock said catch counter clockwise, and thereby disengage its shoulder 88 from the point 89 on the latch plate 72. Upon release of this catch 71, the restoring spring 66, having been put under extra tension, acts and rocks the lever 63, the shaft 64, the arm 62 and the arm 70 clockwise to their normal positions. The movement of the arm 62 through the rod 61 rocks the arms 59 and consequently the differential driver 39 counter clockwise to normal positions. During the last part of the counter clockwise movement of the driver 39 the totalizer engaging and disengaging lever 133 is rocked clockwise to normal position, thereby engaging the tax totalizer with its actuating elements. The flash plate 185 is also lowered by the rocking of the lever 63, through the segments 188 and 189. The "9" indicator target 160 of the amount of the tax and the "90" indicator 218 of the amount of the sale will remain exposed to view until a subsequent operation of the machine, when they will be lowered to normal positions and new indicator targets raised dependent upon the keys depressed.

Should the sale not involve tax the "no tax" key 27 is depressed in place of one of the tax keys 25 or 26 and the mechanism is operated in substantially the same manner as when one of the keys 25 or 26 is depressed, except that no amount will be accumulated upon the tax totalizer. However, it is necessary to depress this "no tax" key in order to unlock the key coupler 199 so that one of the keys 195 may be depressed to register the ordinary amount of the sale involving no tax and therefore the "no tax" target will be exposed to view showing that the merchant sold a non-taxable article.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described, the combination of two series of depressible keys, normally ineffective locking means common to all keys of both series, a main operating member, locking means therefor, means operated by the depression of any key in either series of keys for rendering the key locking means effective and for releasing the locking means for the main operating member, and means operated by the main operating mem-

- ber for releasing an operated key of either series.
2. In a machine of the class described, the combination of two series of keys, an operating member common to one series of keys, a pivoted member for normally holding said operating member against operation, means operated by any key of the second series of keys for releasing the operating member and locking the operated key of said second series of keys in the operated position, and means operated by said operating member for releasing the operated key of the second series.
3. In a machine of the class described, the combination of a main operating member normally inoperative, a plurality of keys, a totalizer, an actuator therefor, a single member interposed between each of said keys and said actuator for differentially positioning said actuator and disengaging the totalizer, means operated by said single member for rendering the main operating member operative and for locking said single member in the operated position, and means operated by the main operating member for releasing said single member.
4. In a machine of the class described, the combination of two series of keys, locking means common thereto, a normally inoperative operating member, two series of members operated by said series of keys, means common to said series of members and operated thereby to operate the key locking means and render the operating member operative, and means operated by said operating member for releasing said key locking means.
5. In a machine of the class described, the combination of two series of keys, locking means common thereto, a normally inoperative operating member, two series of members operated by said two series of keys, means common to said two series of members and operated thereby to operate the key locking means to lock a key of either series in the operated position and to release the operating member, and means operated by said operated member for releasing said key locking means.
6. In a machine of the class described, the combination of a series of keys, a pivoted locking member therefor, cam means actuated by said keys for moving said locking member into locking position, main operating means, a locking member therefor, and means adapted to be contacted by said key locking member to move the second mentioned locking member to release said operating means.
7. In a machine of the class described, the combination of a series of keys, a normally inoperative locking member therefor, main operating means, a pivoted locking member therefor, means operated by said key locking member for releasing said operating means locking member, and means carried by the operating means locking member for releasing the key locking member.
8. In a machine of the class described, the combination of a series of keys, a normally inoperative locking member therefor, main operating means, a locking member therefor, means operated by said key locking member for releasing said operating means locking member, and means carried by the operating means locking member for releasing the key locking member, said last mentioned means operated by the main operating means.
9. In a machine of the class described, the combination of two registering mechanisms, a series of keys for each of said mechanisms for controlling the amount to be entered therein, a member common to each of said series of keys each member being operated by the operation of keys of its appropriate series, means normally locking one of said members, and means for locking the other of said members, said first locking means being disabled by an operation of the other locking means.
10. In a machine of the class described, the combination of two registering mechanisms, a series of keys for each of said mechanisms for controlling the amount to be entered therein, a member common to each of said series of keys each member being operated by the operation of keys of its appropriate series, and means normally locking one of said members, said locking means being disabled by a complete depression of the keys of the other series.
11. In a machine of the class described, the combination of two series of depressible keys, normally ineffective locking means common thereto, a main operating member, locking means therefor, a single means effective when a key in each series is being depressed for compelling a simultaneous depression thereof, for rendering the key locking means effective, and for releasing the locking means for the main operating member, and means operated by the main operating member for releasing the key locking means.
12. In a machine of the class described, the combination of two series of amount controlling devices, means for locking one series of said devices until operation of the other series of devices, a single means for unlocking the first mentioned series of devices and locking the second series of devices by operation of said second series of devices, and means operated by the first mentioned series of devices for releasing the second series of devices.
13. In a machine of the class described, the combination of two series of keys, a single means for locking out one series of keys, means for unlocking said series of keys and simultaneously locking in the other series of keys.

keys, said plurality of locking means involving a common holding member and means operated by the first mentioned series of keys for releasing the second series of keys.

- 5 14. In a machine of the class described, the combination of two series of keys, means for locking out one series of keys, a single means operated by the second series of keys for disabling said locking means and simultaneously locking in said second series of keys, said last mentioned locking means being disabled by an operation of keys of the first series and a member rigid with the frame of the machine with which said locking means cooperate.

- 15 15. In a machine of the class described, the combination of a plurality of series of manipulative amount determining devices, means for preventing the operation of any 20 of the devices in one series until one of the devices of another series has been fully depressed, means for locking the devices of the last-named series when operated, and means controlled by any of the devices of the first 25 mentioned series for releasing the operated devices of the last mentioned series.

16. In a machine of the class described, the combination of a plurality of registering mechanisms, a series of keys for each of said 30 mechanisms, means for preventing the operation of the keys of one of said registering mechanisms until the keys of another of said registering mechanisms have been operated to effect registration, means for locking the 35 keys of the second registering mechanism when operated, and means common to the keys of the first mentioned registering mechanism for unlocking the operated keys of the last mentioned registering mechanism.

- 40 17. In a machine of the class described, the combination of two series of amount controlling devices, two totalizers, actuators therefor, said actuators operated by said devices to control the totalizers, means for locking 45 one series of devices, means for unlocking the said one series of devices and locking the other series of devices by a totalizer actuating operation of said second series of devices, and means operated by the first mentioned series of devices for releasing the second series of devices.

- 50 18. In a machine of the class described, the combination of two dissimultaneously operable series of keys, a totalizer for each series, 55 actuators for each totalizer operable dissimultaneously, said actuators operated by the keys to control the totalizers, means for locking out one series of keys, means for simultaneously unlocking said series of keys 60 and locking in the other series of keys, and means operated by the first mentioned series of keys for releasing the second series of keys.

- 65 19. In a machine of the class described, an 65 combination of two series of keys, an

operating member normally inoperative and common only to one series of keys, means operated by the second series of keys for rendering the operating member operative and locking the second series of keys in the operative position, and means positively operated by said operating member for releasing the operated keys of the second series and locking the first mentioned series of keys.

- 70 20. In an accounting machine, the combination of a plurality of manipulative means, a rockable member, pivotally connected to each manipulative means and operated thereby, a totalizer, an actuator therefor, a cam surface on each member for actuating said totalizer actuator, and another cam surface on each member for moving the totalizer into and out of engagement with the actuator.

- 75 21. In an accounting machine, the combination of a plurality of manipulative means, a rockable member pivotally connected to each manipulative means and operated thereby, a totalizer, an actuator therefor, means on each member for actuating said totalizer actuator, and a cam means on each member for moving the totalizer into and out of engagement with the actuator.

- 80 22. In a machine of the class described, the combination of a plurality of accumulating devices for receiving item entries, means normally operative to enter items in one of said devices, means for entering items in another of said devices, and means preventing an operation of said second item entering means prior to a completion of an item entering operation of said first mentioned device.

- 85 23. In combination, two series of keys, a pivoted catch normally preventing depression of keys of one series, and another pivoted catch for releasing said first mentioned catch and for holding keys of the other series depressed.

- 90 24. In combination, two series of keys, means for preventing depression of keys of one series prior to a depression of keys of the other series, and means operated by the second mentioned series for rendering said first mentioned means ineffective and for retaining keys of said series depressed prior to completion of an operation of keys of the first mentioned series, each of said means comprising a pivoted catch supported on a pivoted arm.

- 95 25. In combination, a plurality of keys, a totalizer, an actuator therefor, an arm operatively connected to the totalizer to control its engagement with said actuator, and a movably mounted driver associated with each key for actuating said arm, said drivers being provided with cam slots, said arm being provided with a rod co-operating with the cam slots to control the arm from any one driver.

- 100 26. In combination, a plurality of keys, a corresponding number of pivoted drivers to 100

which said keys are connected, a totalizer, an actuator therefor, a movably mounted rod operably connected to the totalizer to control its engagement with said actuator, and cam 5 surfaces on said drivers cooperating with said rod.

27. In a machine of the class described, the combination of depressible keys; a differential driver connected to each key; a latch 10 common to all the keys for latching the differential driver and the key in their operated positions; a main operating means; a member to normally prevent the operation of the main operating means; connections 15 between the differential driver and the latch to move the latch into latching position upon operation of any key and differential driver, and to move the member into unlatching position to release the main operating means; 20 and means operated by the main operating device to release the latch to permit the differential driver and the key to return to normal positions.

28. In a machine of the class described, 25 the combination of two registering mechanisms, a series of keys for each of said mechanisms, a normally locked member common to all the keys of one series of keys, a device common to all the keys of the other series of 30 keys, means operated by a complete depression of a key in the second-mentioned series to operate the device to unlock the member, and means to prevent a complete operation of the device until the member is operated 35 by one of its appropriate keys.

In testimony whereof I affix my signature.
BERNIS M. SHIPLEY.
